INVENTOR

Charles D. Cowan.

UNITED STATES PATENT OFFICE.

CHARLES D. COWAN, OF BROCKTON, MASSACHUSETTS, ASSIGNOR OF ONE-HALF TO RUFUS G. SHEPARD, OF SAME PLACE.

COMPOUND BOILER FOR GENERATING STEAM.

SPECIFICATION forming part of Letters Patent No. 282,276, dated July 31, 1883.

Application filed May 25, 1883. (No model.)

To all whom it may concern:

Be it known that I, CHARLES D. COWAN, a citizen of the United States, residing at Brockton, in the county of Plymouth and State of Massachusetts, have invented a new and useful Improvement in Compound Boilers for Generating Steam, of which the following is a specification.

My invention relates to that class of boilers with which auxiliary heaters are used, the object being to economize in fuel, and to so arrange the parts that there will be no noise from the steam that may be generated in the auxiliary heater. I attain these objects by the mechanism illustrated in the accompanying drawings, in which—

Figure 1 is a view of my invention in elevation and section. Fig. 2 is a horizontal section taken on line *x y* of Fig. 1.

A represents a tubular boiler set in brick, as shown. B is a bank of tubes into which the water-supply of the boiler enters at E, and after circulating through this bank of tubes passes through the pipe H to the boiler A. The pipe H terminates in a vertical pipe, H' H'', the lower end of which, H', enters the boiler below the water-line, while the upper end, H'', enters the steam-pipe at L. I have made this

arrangement so that in case any steam may be formed in the auxiliary heater B it may pass directly to the steam-pipe L M, and not go through the boiler A. This arrangement prevents all noise in the boiler A. The water of condensation passes through the pipes P P' P'' back to the auxiliary heater B. The action of the fire in my improved device is to send heat from the furnace N through the tubes in the boiler A, thence over the bridge at arrow D, around the tubes B of the auxiliary heater, thence in the direction of the arrow at K to the smoke-stack. The heated products of combustion, after leaving the boiler A, transmit a large part of their caloric to the water in the heater B, and it is in this characteristic that I deem my device as an improvement on any ever made.

I claim as my invention—

In a steam-generating device, the combination of the boiler A, the pipes H', H'', and H, with the auxiliary heater B, and fire-passages D and K, all arranged substantially as described, and for the purpose set forth.

CHARLES D. COWAN.
